UNITED STATES PATENT OFFICE.

ROBERT L. BAILEY, OF PORTLAND, OREGON, ASSIGNOR TO A. L. MACLEOD, OF PORTLAND, OREGON.

DESIGN FOR A MOTOR-CYCLE FRAME.

43,262.

Specification for Design.

Patented Nov. 26, 1912.

Application filed April 24, 1912. Serial No. 692,986. Term of patent 14 years.

To all whom it may concern:

Be it known that I, ROBERT L. BAILEY, a citizen of the United States, residing at Portland, in the county of Multnomah and State of Oregon, have invented a new, original, and ornamental Design for Motor-Cycle Frames, of which the following is a specification, reference being had to the accompanying drawings, forming a part thereof, in which—

The figure is a side view of a motor cycle frame, showing my design.

I claim:

The ornamental design for a motor cycle frame, as shown.

ROBERT L. BAILEY.
